NONSPILLABLE INKWELL

John E. Williams, Wellesley, Mass.

Application December 24, 1943, Serial No. 515,471

5 Claims. (Cl. 120—57)

The present invention relates to inkwells which are normally open in order that the liquid kept therein may at all times be available for access by dipping. More specifically, the invention is concerned with improvements in a non-spillable inkwell whereby the escape of liquid is effectively prevented even though the inkwell be accidentally tipped, rolled, or otherwise disturbed, even in relatively violent fashion. The invention is likewise concerned with improvements whereby smudging of the penholder during use of the inkwell is prevented.

According to the invention, the inkwell is substantially spherical in shape, in marked distinction to prior devices of this category. Preferably both the exterior and the interior are spherical, but in any event the interior, except as will appear hereinafter, is spherical or nearly so, in order that wave formation and sloshing of the ink in case of accidental tipping or rolling of the inkwell may be minimized.

To provide access to the ink within, the inkwell is provided with an opening which includes a reentrant tube or passage for the pen point and lower end of the pen holder. This tube, which likewise serves to hold the pen when the latter is not in use, is so constructed and arranged as to be substantially free from wetting by the ink, not only during normal use of the inkwell involving repeated removal and replacement of the pen in replenishing the ink on the pen point, but also under conditions of abnormal position of the inkwell and its contents.

In the drawing illustrating the invention, Fig. 1 is a sectional view showing the inkwell in normal position with a pen therein ready for use; Fig. 2 is a view showing the inkwell tipped forward to a position in which the opening for the pen is substantially horizontal without permitting the escape of ink; and Fig. 3 is a view of a slightly modified construction, the inkwell being shown in inverted position to illustrate further the retention of ink under abnormal attitudes of the inkwell.

As has already been indicated, the inkwell comprises a substantially spherical body 6 which is preferably formed of a transparent material such as glass. The spherical body is slightly flattened, as at 8, to provide a base to assist in defining and maintaining a normal position of the inkwell.

To provide convenient access to the ink at all times, a permanent opening is provided in the upper portion of the body at an angle to the vertical. Escape of ink through this opening is prevented, even though the inkwell be inverted,

by a reentrant tube 10 extending from the rim of the opening approximately to the center of the inkwell body.

According to the embodiment illustrated in Fig. 1, the tube 10 may be made separately from the body 6 and subsequently secured to a narrow upstanding rim or bead 12 extending around the opening in the well body. The tube may be formed of any suitable material, such as metal, glass, plastic or the like, and may be secured by rolling its outer end over the rim 12, or by fusing to the body 6. The tube is shaped to provide a flaring mouth, and likewise a flaring lower or inner end, to afford to the pen some angular freedom within the tube, even though the tube, in the region of reduced diameter 14, be substantially closed by the body of the pen holder 16 to minimize evaporation during periods of non-use.

20 To prevent smudging of the penholder by ink that may be deposited within the tube in withdrawing the pen, longitudinal ridges 18 may be formed in the tube to provide limited area of contact between tube and penholder. Preferably 25 the ridges have relatively sharp edges to cause any ink thereon quickly to be drawn by surface tension down into the grooves between ridges, and thence to the lower end of the tube. This end of the tube flares somewhat beyond the limit 30 of movement of the penholder, so that contact between the penholder and the inner end of the tube is effectively prevented.

Further protection against the escape of ink into the tube, particularly when the inkwell is 35 tipped or disturbed, is afforded by a reverse flare or skirt 20 at the lower end of the tube. This skirt serves as a trap or baffle to prevent ink sloshing over into the tube. The lowermost portion of the skirt, with the well in normal position, 40 is bent downward slightly below the horizontal to provide a lip or horn 22 for diverting any ink that may have run down the tube, either from the ridges within or from the skirt outside the tube, to a "dropping-off" point for return to the supply. The ridges and the skirt thus cooperate 45 in maintaining the tube free of ink.

The ink level in the well is preferably slightly 50 below the rim of the tube, so that with a pen resting in the well with its point against the interior of the well opposite the tube, the penholder is out of contact with the ink but the point is substantially covered, so as to take up a full charge of ink when the pen is withdrawn. To facilitate access to the ink when the supply 55 is low, and particularly to aid in replenishing

fountain pens from the well, the body 6 is formed with a thickened bottom having a sump 24 so positioned as to receive the pen point of a pen that is introduced in a more nearly vertical position than the normal resting position of a pen. The thickened bottom portion likewise affords stability by reason of its added weight, in case the inkwell is formed of some relatively dense material such as glass.

By limiting the filling of the inkwell to the level above described, the well may be tipped on its side (Fig. 2) or fully inverted (Fig. 3) without at any time providing an opening below the level of the ink. Due to the spherical external shape, the device, if tipped, rolls smoothly without causing violent agitation of the ink within, while the smooth spherical interior contributes to the prevention of wave formation and sloshing. It will be understood that waves, if formed, would tend to cause splashing of the ink into the tube and perhaps result in the escape of ink to the exterior.

Fig. 3, in addition to showing the operation of the inkwell in inverted position, illustrates an alternative embodiment in which the reentrant tube is integral with the body. This construction may be effected either by making tube and body as one piece, or by making the parts separately and then fusing the tube to the body adjacent the rim 26 to provide a homogeneous construction. As an alternative to the protective skirt surrounding the inner end of the tube, the tube is formed with a sharp knife-like edge 28 which prevents the passage of ink from the exterior to the interior of the tube. At the lower-most position of the tube, with the well in normal position, a horn or lip 30 may be provided as in the previously described embodiments to direct the ink away from the tube and into the reservoir.

Fig. 3 likewise illustrates the preferred position of the inkwell in case it is desired to let the well remain for long periods of time without a pen therein, or where the well is used solely as a reservoir for the filling of fountain pens. With the inkwell in inverted position, the device is substantially self-sealing, and evaporation is slight.

I have thus indicated as my invention an inkwell which by its novel configuration, quite at variance with the usual shape of containers that are normally open at all times for access to the liquid therein, is substantially non-spillable. In addition, means have been shown for preventing the ink from reaching areas that are apt to be engaged by the penholder, and thus any wetting or smudging of the penholder is avoided.

What is claimed is:

1. A non-spillable inkwell comprising a substantially spherical hollow body having an externally flattened and thickened wall portion to provide a weighted stable base, said body having a normally open passage to provide access to the interior, said passage being defined by a reentrant tube extending inwardly of the body substantially to the center thereof, the tube having a restricted throat portion intermediate its ends sufficient to accommodate the body of a penholder and increasing in diameter from said throat portion toward the ends, and inwardly projecting longitudinal ridges within the tube for supporting a penholder out of contact with the body of the tube, the inner end of the tube terminating at an acute angle beyond said ridges and said end

portion of the tube lying outside the range of movement of a penholder within the tube.

2. A non-spillable inkwell comprising a substantially spherical hollow body having an externally flattened and thickened wall portion to provide a weighted stable base, said body having a normally open passage to provide access to the interior, said passage being defined by a reentrant tube extending inwardly of the body substantially to the center thereof, the tube having a restricted throat portion intermediate its ends sufficient to accommodate the body of a penholder and increasing in diameter from said throat portion toward the ends, and inwardly projecting longitudinal ridges within the tube for supporting a penholder out of contact with the body of the tube, the ridges terminating short of the inner end of the tube and said inner end portion of the tube beyond the ridges lying outside the range of movement of a penholder within the tube.

3. A non-spillable inkwell comprising a substantially spherical hollow body having an externally flattened and thickened wall portion to provide a weighted stable base, said body having a normally open passage to provide access to the interior, said passage being defined by a reentrant tube extending inwardly of the body substantially to the center thereof, the tube having a restricted throat portion intermediate its ends sufficient to accommodate the body of a penholder and increasing in diameter from said throat portion toward the ends, and inwardly projecting longitudinal ridges within the tube for supporting a penholder out of contact with the body of the tube, the inner end of the tube lying outside the range of movement of a penholder within the tube and terminating in a sharp edge.

4. A non-spillable inkwell comprising a substantially spherical hollow body having an externally flattened and thickened wall portion to provide a weighted stable base, said body having a normally open passage to provide access to the interior, said passage being defined by a reentrant tube extending inwardly of the body substantially to the center thereof, the tube having a restricted throat portion intermediate its ends sufficient to accommodate the body of a penholder and increasing in diameter from said throat portion toward the ends, and inwardly projecting longitudinal ridges within the tube for supporting a penholder out of contact with the body of the tube, and a reversely flaring skirt extending around the tube at the inner end thereof.

5. A non-spillable inkwell comprising a substantially spherical hollow body having an externally flattened and thickened wall portion to provide a weighted stable base, said body having a normally open passage to provide access to the interior, said passage being defined by a reentrant tube extending inwardly of the body substantially to the center thereof, the tube having a restricted throat portion intermediate its ends sufficient to accommodate the body of a penholder and increasing in diameter from said throat portion toward the ends, inwardly projecting longitudinal ridges within the tube for supporting a penholder out of contact with the body of the tube, said ridges terminating short of the inner end of the tube, the end portion of the tube lying outside the range of movement of a penholder within the tube and terminating in a sharply-intersecting skirt having a reverse flare.
